CLAIM

The ornamental design for a jumbo debris pan, as shown and described.

DESCRIPTION

FIG. 1 is a perspective view of the jumbo debris pan of the subject invention.

FIG. 2 is a rear view of the jumbo debris pan of FIG. 1.

FIG. 3 is a bottom view of the jumbo debris pan of FIG. 1.

FIG. 4 is a top side view of the jumbo debris pan of FIG. 1.

FIG. 5 is a front side view of the jumbo debris pan of FIG. 1; and,

FIG. 6 is a left side view of the jumbo debris pan of FIG. 1; and, FIG. 7 is a right side view of the jumbo debris pan of FIG. 1. The broken line showing of FIGS. 1, 2, 4, 5, 6 and 7 is for the purpose of illustrating environment and forms no part of the claimed design.
